UNITED STATES PATENT OFFICE.

ISHMAEL W. MACY, OF GALION, OHIO, ASSIGNOR TO THE GALION IRON WORKS & MFG. CO., OF GALION, OHIO, A CORPORATION OF OHIO.

BUCKET-CONTROLLED SPOUT.

Application filed May 1, 1928. Serial No. 274,318.

This invention relates to material handling structures of that character wherein the material to be handled is discharged from cars into a hopper having a spout, in turn discharging into a bucket disposed within a pit, the bucket being hoisted from the pit by suitable hoisting mechanism which forms no part of the present invention and discharging into a bin in which the material is stored until required for use, and the invention particularly relates to means for automatically shifting the spout to a discharge position when the bucket enters the pit and automatically closing or raising the spout to a cut-off position when the bucket is hoisted from the pit.

The general object is to provide a spout formed in a plurality of sections, certain of the sections being pivoted and normally held in a raised position, and provide means actuated by the descent of the bucket into the pit to shift the pivoted sections of the spout in a downwardly inclined position whereby the material shall be discharged into the upper end of the bucket, the spout being so constructed as to prevent the discharge of material until the bucket has been fully lowered.

A further object is to provide means actuated by the bucket itself when it is lifted from the pit acting to positively lift the spout and shift the sections to a cut-off position.

A still further object is to provide means normally supporting the sections of the spout in a raised position, which means is adapted to be engaged by rollers on the sides of the bucket and shifted downward by the descent of the bucket into its fully lowered position in the pit, which means is provided with jaws with which the rollers on the bucket are adapted to engage, causing the positive and certain actuation of the spout-supporting means when the bucket is lowered into the pit or rises therefrom, these jaws being so constructed as to prevent any possible jamming of the rollers between the guide rails of the pit upon which the rollers move, said jaws doing away with the necessity of careful fitting of the various parts.

Other objects have to do with the details of construction and arrangement of parts as will appear more fully hereinafter.

My invention is illustrated in the accompanying drawings, wherein:—

55

Figure 1 is a vertical sectional view through a hopper showing my improved spout and bucket in elevation, the spout being lowered;

Figure 2 is a like view to Figure 1, the spout being raised;

Figure 3 is a like view to Figure 1 but showing the several sections of the spout in section;

Figure 4 is a detail view of the outer end 65 of one of the lifting arms, the upper end of the lifting arm being broken away;

Figure 5 is a like view to Figure 3 but showing the spout in its fully raised and cut-off position;

70

Figure 6 is a section on the line 6—6 of Figure 3;

Figure 7 is a section on the line 7—7 of Figure 3;

Figure 8 is a front elevation of the cut-off 75 section.

Referring to these drawings, 10 designates the hopper into which material, such as coal, is discharged from railway cars. This hopper is provided with the upwardly and forwardly inclined front wall 11, though I do not wish to be limited to an upwardly inclined front wall, having thereon guides 12 and a gate 13, this gate being shown as being adjustable by means of a screw-threaded rod 85 14 which is adjustably engaged with the gate and which is rotatable by a crank or other suitable means. This rod is supported in collars carried by a bracket 15.

The front wall 11 is provided with an 90 opening 16, and fitting this opening is the chute 17, this chute being U-shaped in cross section, that is, being provided with a bottom and two sides but being open at the top. The chute at its outer end is reinforced 95 by a transverse bar 18 having depending legs 19 riveted to the walls of the chute. Mounted upon the inside walls of the chute are the bearings 20. Disposed more or less adjacent the upper forward corner of the 100 chute and disposed between the bearings 20 and the lower rear corner of the chute and upon the outside faces thereof are the end bearings 21 for the operating arms.

Extending from the bearings 21 are shafts 105 22 and disposed on each side of the chute 17

are the castings 23. These castings are articulate on their lower faces and carry the intermediate spout section 24. The upper and inner corners of the castings 23 are formed to provide bearings 25^a upon which these castings rock and the lower forward corner of each casting 23 is formed with a bearing 25 for the passage of a transversely extending stub shaft 26 constituting a pivot upon which the spout 27 is mounted. This spout 27 is also U-shaped in cross section and is reinforced at its rear margin by a U-shaped bar 28, the legs of this bar having openings 29 through which the shaft 26 passes. Thus it will be seen that the spout 27 is pivoted to the section 23 and this in turn is pivoted to the section 17, the section 23 being pivoted at its upper rear corner to the section 17, while the spout is pivoted at its lower rear corner to the section 23.

It will be seen that the intermediate section 24 with the spout section 27 forms, when the intermediate section and the spout section turn to the position shown in Figure 2, a cut-off, the intermediate section 24 acting to bridge the gap between the lower end of the spout section 27 and the forward end of the chute section 17 when the spout section 27 is turned in the position shown in Figure 2.

Disposed on each side of the spout sections 17, 23 and 27 are the operating arms 30. These arms at their rear ends are pivoted to the castings 21 and project beyond the forward end of the spout 27. Each arm consists of a channel iron having a bearing bracket 31 attached to its rear end by which it is pivoted to the corresponding casting 21. Riveted or otherwise attached to the middle of each arm 30 is a plate 32, this plate being approximately triangular in form above the corresponding arm. Extending around the spout 27 is a yoke consisting of an upper cross beam 33 shown as T-shaped in cross section, a lower channel iron 34, and two pairs of channel irons 35 operatively engaged with the upper and lower beams 33 and 34. The channel irons of each pair are spaced apart, as shown in Figure 6.

The arms 30 with the plates 32 are disposed against the outside channel irons 35, the plates being riveted to these channel irons, and pivot members 36 extending through suitable bearings in the irons 35 and in the arm 30 and engaging with the spout 27. Thus the yoke 37 formed of the members 33, 34 and 35 is rigidly engaged with the operating arms 30 and disposed at right angles thereto, and these operating arms in turn pivotally engage with the bucket, the yoke being of such character as to give an abundance of support to the pivots 36 upon which the spout 27 is mounted.

This yoke 37 at its upper end supports a sheave 38 over which a cable 39 passes, this cable passing upward and over suitable

sheaves 40 attached to a sheave support 41, and the cable then extending down over a guiding sheave 42 to a weight 43 which is of sufficient weight to counterbalance the spout, the operating arms 30 and the yoke.

To the outer ends of the arms 30 are attached the spaced plates 44. These plates extend outward of the corresponding arm 30 and are riveted thereto so as to form part thereof, and between the lower projecting ends of the plates 44 is pivoted the lower jaw 45. The plates 44 are extended upward above the channel iron arm 30 and then forwardly extended and these forwardly extending lugs 46 have pivoted between them the upper jaw 47 which confronts the jaw 45. This upper jaw has a tail or extension 48 which extends upward and inward and through which passes the stop screw 49 adapted to bear against a separator 50 mounted between the plates 44. This will permit the jaw 47 to swing downwardly and inwardly but prevents it swinging upward, as clearly shown in Figure 4.

Disposed within the pit A opposite the lower portion of the hopper and opposite the spout are the upwardly and laterally inclined rails 51. The bucket 52 (which bucket is fully described and illustrated in my pending application for patent, Serial #275,477 filed on the fifth day of May, 1928) is provided on its sides with the outwardly projecting rollers 53. The bucket is supported by a sheave 54 and cable 55. The bucket is open at its top upon one side, as at 56, and it is into this open portion of the top of the bucket that the spout 27 discharges when the bucket and the spout are both lowered to the proper position.

When the bucket is lowered into the pit, the rollers will strike the downwardly inclined rails 51 and then as the bucket lowers the rollers will bear against the lower portions of the pivoted jaws 47, forcing the lower portions inward and permitting the rollers to move downward upon the rails 51 until they strike the lower jaws 45. These lower jaws 45 can swing outward to a position against the rails so that there is no possible chance for the rollers to escape past the lower jaws 45 and the rollers must engage these lower jaws so that as the bucket continues to lower, these rollers bearing against the lower jaws 45 will force the operating arms downward. This, through the pivots 36, will act to turn the sections 27 and 23 downward from the position shown in Figure 2 to a position where the cut-off section 23 and the spout section 27 are both in alignment with the chute 17 and discharge downwardly and laterally into the upper end of the bucket.

When the bucket is filled and is drawn upward, the rollers 53 move up the rails 52 and in doing so strike the jaws 47. These

jaws cannot turn inward because of the stop screws on the jaws and hence the rollers must under these circumstances lift the arms 30 from the position shown in Figure 1 to that shown in Figure 2. This turns the spout section 27 upon its pivot 26 and turns the cut-off section 23 upon its pivot 22 until the spout has arrived at the position shown in Figure 2. At this time the arms 30 have moved up so high that the rollers 53 can escape from the jaws 47 and the bucket moves upward, leaving the spout in its raised position where it remains until the bucket is again lowered. When the spout is lifted, the cut-off section and the inclination of the spout 27 prevent all discharge of coal or other material until the spout is again lowered.

It will be seen that this action is purely automatic, that the operator does not have to control the spout in any manner but simply lowers the bucket into the pit and that this automatically opens the spout, and when the bucket is raised the spout becomes automatically closed and the discharge of coal or other material cut off. The means whereby the bucket is raised and traverses so as to discharge over a bin and the means whereby the bucket is emptied from the subject-matter of separate applications for patents filed of even date herewith.

While I have illustrated a structure of this character which has been found to be particularly effective and in which the details have all been designed to secure the end desired, I do not wish to be limited to these details as it is obvious that they might be varied in many ways without departing from the spirit of the invention.

40 I claim:—

1. In combination, a spout formed in a plurality of sections pivoted to each other, arms extending on each side of the spout and pivotally supported at their inner ends on fixed pivots and intermediate their ends pivoted to one of the sections of the spout, a bucket adapted to receive material from the spout, the bucket and arms having coacting means causing the bucket to engage the arms upon the descent of the bucket to thereby lower the spout to discharge position, the bucket upon its ascent raising the arms and raising the spout out of a discharge position.

2. The combination with a receptacle having a downwardly extending discharge chute, an intermediate section pivotally mounted upon the chute for movement from a discharge to an upwardly inclined position, a spout section pivotally mounted upon the intermediate section and adapted to be lowered to form a continuation of the chute and intermediate or raised into a position at an angle to the chute, a bucket, and means on the bucket adapted to operatively engage the spout section when the bucket is lowered

to automatically turn the spout section and the intermediate section into a downwardly and outwardly inclined position of alignment with the chute, the raising of the bucket automatically acting to lift the spout section and the intermediate section into an angular relation to the chute.

3. The combination with a receptacle having a chute extending downward and outward therefrom, of an intermediate section pivotally connected to the chute, a spout section pivotally connected to the intermediate section, laterally disposed arms pivotally mounted upon the chute and extending on each side of the intermediate and spout sections and pivotally connected to the spout section, a bucket, and coacting means on the extremities of the arms and on the bucket acting to cause a depression of said arms and a depression of the spout section and intermediate section into alignment with the chute when the bucket is lowered to a receiving position and acting to lift the arms and turn the spout section and the intermediate section into a position at an angle to the chute when the bucket is raised.

4. The combination with a receptacle having a chute extending downward and outward therefrom, of an intermediate section having sides and an arcuate bottom pivotally connected at its upper corner to the chute for swinging movement from a position in approximate alignment with the chute into relatively angular position or vice versa, a spout section pivotally connected at its lower rear corner to the intermediate section, arms pivoted at their rear ends to the chute and extending outward on each side of the intermediate and spout sections, the arms being pivoted to the spout section, a yoke attached to said arms and arching over the spout section, a counterweight operatively connected to the yoke, a bucket adapted to receive material from the spout when the spout is lowered, the bucket and arms having coacting means whereby upon a lowering of the bucket the outer ends of the arms may be lowered to thereby lower the intermediate section and spout section into approximate alignment with the chute and whereby when the bucket is raised the spout section and intermediate section will be turned into angular relation to the axis of the chute to thereby cut off the discharge of the material from the chute.

5. The combination with a receptacle having a downwardly and outwardly inclined chute, an intermediate section embracing the chute and pivotally connected at its upper rear corner thereto, a spout section pivotally connected to the intermediate section at its forward lower corner, arms pivotally supported at their inner ends and intermediate their ends being pivoted to the spout section forward of its point of pivotal engagement

with the intermediate section, downwardly and inwardly inclined tracks supported opposite the spout, a bucket lowerable between said tracks and having laterally projecting rollers adapted to engage the same, each of the arms having an upper jaw and a lower jaw between which the rollers are adapted to engage as the bucket is lowered to receiving position to thereby lower the intermediate section and the spout to discharge into the bucket, the upward movement of the bucket causing the lifting of the arms and the consequent lifting of the spout and intermediate until the rollers escape from the said upper jaws.

6. A receptacle having a discharge chute, an intermediate section embracing the chute and pivotally connected at its upper rear corner to the chute, a spout section pivotally connected at its lower rear corner to the intermediate section, a pair of arms pivotally supported at their inner ends and extending outward beyond the spout section, the arms being pivotally connected to the spout section, a yoke attached to the arms and embracing the spout section, a counter-weight operatively connected to the yoke, members connected to the outer ends of the arms and supporting upper and lower pivoted jaws, a downwardly and inwardly inclined track, and a bucket having laterally projecting wheels adapted to engage the track and engaging the lower jaws of the arms as the bucket descends to thereby depress the arms and depress the spout and cut-off and engaging the upper jaws as the bucket ascends to cause the positive lifting of the arms and the consequent swinging upward movement of the spout and intermediate.

7. A receptacle having a discharge spout and intermediate section embracing the chute and pivotally connected at its upper rear corner to the chute, a spout section pivotally connected at its lower rear corner to the intermediate section, a pair of arms pivotally supported at their inner ends and extending outward beyond the spout section, the arms being pivotally connected to the spout section, a yoke attached to the arms and embracing the spout section, a counter-weight operatively connected to the yoke, members connected to the outer ends of the arms and supporting upper and lower pivoted jaws, a downwardly and inwardly inclined track, a bucket having laterally projecting wheels adapted to engage the track and engaging the lower jaws of the arms as the bucket descends to thereby depress the arms and depress the spout and intermediate and engaging the upper jaws as the bucket ascends to cause the positive lifting of the arms and the consequent swinging upward movement of the spout

and intermediate, the lower jaw being pivoted at its lower end for outward swinging movement toward the corresponding rail, the upper jaw being pivoted for inward swinging movement when engaged by the roller, and means adjustably limiting the outward movement of each upper jaw.

8. In combination with a chute, a spout operatively connected to the chute and adapted to be moved into angular relation to the chute to prevent discharge therefrom, arms pivoted to the spout and pivotally mounted at their rear ends upon said chute, the arms projecting beyond the spout, counterbalancing means connected to said arms and urging them upward, a track extending downward and toward a point below the chute, a bucket adapted to be lowered between said tracks and having rollers engaging the tracks and moving downwardly and laterally upon the tracks, and means engaged by said rollers as the bucket is lowered to receiving position acting to move said arms downward and move the spout to a discharge position and acting as the bucket is raised to raise the arms and move the spout to an upwardly inclined position, said means being so constructed as to permit the free upward movement of the bucket when the spout has been fully raised.

9. In combination, a receptacle having a spout section pivotally supported for vertical movement, arms pivotally supported at their inner ends on fixed pivots and connected intermediate their ends to the spout section, a bucket adapted to be lowered to receive material from the spout section or raised above the same, the arms being engageable by the bucket on its descent and lowered to turn the spout section to a discharge position, said arms when lifted up by the bucket raising the spout section out of its discharge position.

10. In combination, a receptacle having a discharge opening, arms pivotally supported at their inner ends on each side of the discharge opening, a spout section movable from a position with its bottom approximately parallel to the plane of the discharge opening to a position with its bottom downwardly and outwardly inclined, an arm pivoted at its inner end upon a fixed pivot and connected intermediate its ends with the spout section, a bucket movable into position to receive material from the spout section or out of said position, said bucket when lowered past the spout section downward to its downwardly discharging position and when raised lifting said arm and causing the spout section to turn to its cut off position.

In testimony whereof I affix my signature.

ISHMAEL W. MACY.
